(57) **CLAIM**

The ornamental design for a badge holder, as shown and described.

DESCRIPTION

FIG. 1 is a top, right and rear perspective view of the first embodiment of a badge holder embodying our new design; FIG. 2 is a rear elevational view thereof; FIG. 3 is a left elevational view thereof, the right elevational view being a mirror image thereof; FIG. 4 is a front elevational view thereof; FIG. 5 is a top plan view thereof; FIG. 6 is a bottom plan view thereof; FIG. 7 is a top, right and rear perspective view of the second embodiment of a badge holder embodying our new design; FIG. 8 is a rear elevational view thereof; FIG. 9 is a left elevational view thereof, the right elevational view being a mirror image thereof; FIG. 10 is a front elevational view thereof; FIG. 11 is a top plan view thereof; and, FIG. 12 is a bottom plan view thereof. The broken line representations in the views are for illustrative purposes only and form no part of the claimed design.
